(57) **CLAIM**

The ornamental design for an hexagonal water storage module, as shown and described.

DESCRIPTION

FIG. 1 is a perspective view of an hexagonal water storage module;

FIG. 2 is a front elevation view thereof;

FIG. 3 is a right elevation view thereof, the left end elevation view being identical thereto; and,

FIG. 4 is a bottom plain view thereof.

1 Claim, 4 Drawing Sheets

FIG. 1FIG. 2

FIG. 3FIG. 4
